UNITED STATES PATENT OFFICE.

JOHN FRANKLIN BUTTON, OF ARDMORE, INDIAN TERRITORY.

DESIGN FOR A HARNESS-LOOP.

SPECIFICATION forming part of Design No. 33,028, dated July 31, 1900.

Application filed May 4, 1900. Serial No. 15,548. Term of patent 7 years.

To all whom it may concern:

Be it known that I, JOHN FRANKLIN BUTTON, a citizen of the United States, residing at Ardmore, Chickasaw Nation, Indian Territory, have invented and produced a new and useful Design for a Harness-Loop, of which the following is a specification, reference being had to the accompanying drawings, forming part of this application, and in which—

Figure 1 is a perspective view of a harness-loop, showing my design. Fig. 2 is an edge view of the same, and Fig. 3 is an end view.

As shown in the drawings, the leading feature of my design consists of a substantially-rectangular box or flat frame 1, the ends of which are open, as shown at 2, and the bottom is partly open, as shown at 3. The ends

of the bottom where they terminate to form the open space 3 are each provided with a projection 4 at each edge, which extends at right angles thereto and is tapered to a point. The top is creased from the center to each corner, as shown at 5, to cause the center to lie out of the plane of its edges, and the portions between the creases and the edges are ornamented with longitudinal lines, as shown at 6.

Having thus fully described my invention, what I claim, and desire to secure by Letters Patent, is—

The design for a harness-loop, as herein shown and described.

JOHN FRANKLIN BUTTON.
